INVENTOR
Louis V. Aronson,
BY
Friedrich C. Fischer
ATTORNEY

UNITED STATES PATENT OFFICE.

LOUIS V. ARONSON, OF NEWARK, NEW JERSEY.

MECHANICAL EYE.

1,408,794.

Specification of Letters Patent.

Patented Mar. 7, 1922.

Application filed February 11, 1920. Serial No. 357,968.

To all whom it may concern:

Be it known that I, LOUIS V. ARONSON, a citizen of the United States, residing in the city of Newark, county of Essex and State 5 of New Jersey, have invented certain new and useful Improvements in Mechanical Eyes, of which the following is a full, clear, and exact description, such as will enable others skilled in the art to which it pertains 10 to make, construct, and use the same, reference being had to the accompanying drawings, and to numerals of reference marked thereon, forming a part of this specification.

15 The present invention relates to improvements in mechanical eyes for the so called "sleeping dolls", and the object of the invention is to simplify and improve the mechanical eyes, with the view of facilitating the 20 mounting of the mechanical eye in the head.

With these ends in view, my invention consists in certain novelties of construction and arrangements of parts as hereinafter set forth and pointed out in the claims.

25 While the preferred form of my invention is illustrated in the accompanying drawing, yet it is to be understood that minor changes may be made without departing from the scope thereof.

30 In the drawings,

Figure 1 represents, a vertical sectional view of a doll's head showing my improved mechanical eye secured thereto.

Figure 2 is a side elevation, and

35 Figure 3 is a front elevation of the eye and its closing means.

Similar numerals of reference refer to like parts throughout the specification and drawings.

40 In the drawings, 1 represents a hollow doll's head formed as usual with the eye sockets 2, into which my improved mechanical eyes are secured.

The mechanical eye consists of a sheet 45 metal cap 3 formed with an annular rim 4 and with a segmental spheroidal wall 5, having a curved lower flange 6 by means of which the mechanical eye is secured to the eye sockets 2 of the metallic head 1, preferably by means of solder.

The hollow eye member 7, formed of hollow semi-spherical shape, of suitable material, preferably of celluloid, fits snugly in the sheet metal cap 3, within the annular 55 rim 4 and spheroidal wall 5.

The upper movable lid member consists

of a spheroidal segment 8 having at its outer edges perforated lugs 9, in which a pivot rod 10 is supported.

The pivot rod 10 passes through suitable 60 openings formed through the flange of the cap member 3 and the side walls of the hollow eye member 7.

One of the perforated lugs 9 projects rearwardly and downwardly to receive the bent 65 portion of the pivot rod 10, the perforated lug 9 being provided with tongues 14 bent around the rod 10 to secure it to the movable lid member.

The rod 10 carries the counter balance 70 weight 15 which holds the movable lid open when the doll is held upright, and causes the eye lid to close when the head is put in a reclining position.

Experience has demonstrated that the organization above described is a highly efficient one, and while I have shown the preferred embodiment of my present invention, I do not wish to be limited to the exact details of construction shown and described, 80 as obvious modifications thereof, not involving the exercise of invention, may be made by any skilled mechanic, and such departures from what is herein set forth, I consider within the scope and terms of my 85 claims.

Having thus described my invention, what I claim as new and desire to secure by Letters Patent is:

1. The combination with a hollow doll's 90 head formed with eye sockets, cup-shaped members each formed with an annular rim, an eye member secured in the said rim, the cup-shaped member being provided with an integral segmental spheroidal wall having a 95 curved lower flange for securing it to the eye socket of the doll's head, a movable upper lid member pivotally mounted upon said cup-shaped member, and a counter balance for said movable lid member projecting 100 from one side of said lid member.

2. The combination with a hollow doll's head formed with eye sockets, cup-shaped members formed with an annular rim, and an integral segmental spheroidal wall having a curved lower flange for securing it to the eye socket of the doll's head, a hollow eye member of semi-spherical shape secured within the annular rim and spheroidal wall, a movable upper lid member pivotally 110 mounted upon said cup-shaped member, comprising a spheroidal segment having at

its outer edges perforated lugs, a pivot rod passing through said perforated lugs and through the said walls of the eye member, and a counter balance secured to one end of the pivot rod, the pivot rod being secured to the movable lid member by an integral tongue formed on one of the perforated lugs, said tongue being bent around the rod.

This specification signed and witnessed this ninth day of February, 1920.

LOUIS V. ARONSON.
